WEIGHT-CHECKING SCALE

Herbert James Floyd, Coventry, England, assignor to Office Machinery Limited

Filed Apr. 7, 1964, Ser. No. 79,444

Term of patent 14 years

(Cl. D52—10)

FIG. 1.

FIG. 2.

FIG. 1 is a side view in perspective of a weight-checking scale, showing my new design.

FIG. 2 is an end elevational view thereof.

When viewed from the right in FIG. 1, the end of the hood at the upper portion of the scale is substantially flat and plain in appearance.

The side of the scale opposite to that shown in FIG. 1 is substantially the same as the side shown in FIG. 1.

I claim:

The ornamental design for a weight-checking scale, as shown and described.
